Inventor:

John W. Etchells.

By his Attorney
Andrew Wilson.

UNITED STATES PATENT OFFICE.

JOHN W. ETCHELLS, OF BROOKLYN, NEW YORK.

HAT-RACK AND COAT-HOLDER.

1,383,611.

Specification of Letters Patent. Patented July 5, 1921.

Application filed March 8, 1921. Serial No. 450,649.

To all whom it may concern:

Be it known that I, JOHN W. ETCHELLS, a subject of the King of Great Britain, and resident of the borough of Brooklyn, city 5 and State of New York, have invented certain new and useful Improvements in Hat-Racks and Coat-Holders, of which the following is a specification.

My invention relates to improvements in 10 hat racks and coat holders, which are adapted to hold the hat in a loop of wire through which the crown of the hat is passed, and also to provide a hook which serves as a support on which a coat or other 15 garment may be hung; and my improvements are directed particularly to means whereby a simple device combining both these advantages may be formed from a single piece of wire which is doubled and 20 twisted upon itself, as hereinafter explained, so as to secure the results desired, details of the improvements being hereinafter particularly pointed out and claimed.

In the drawings, Figure 1, is a perspective view of my improved device, showing 25 the outline of a hat in broken lines as being held therein; Fig. 2 is a side view of the same, showing it attached to a section of a wall or other backing; and Fig. 3 is a plan 30 view of the article.

The same parts are designated by similar reference numerals in all the figures.

The rack is formed of a single piece of wire, which is first bent so as to constitute 35 a loop, 1, which is adapted to receive the crown of a hat, as shown in the drawing. The wire is then twisted upon itself and bent down, as at 2, and then laterally as at 3, so as to make the loop stand off from the 40 backing to which the device may be secured, thereby allowing space for the brim of a hat to hang free between the loop and the backing without touching the latter.

The strands of the wire are then bent 45 down, parallel to each other as at 4, and re-curved upon themselves to form a hook as 5, after which they are brought up behind themselves, as at 6, and are twisted together as at 7, and next spread out angularly as at 8, and then extended upwardly 50 and provided with suitable holding loops, 9, through which loops fastening elements as 10 may be passed.

It will be seen that by means of my 55 improvements I am enabled to make out of a single integral piece of wire, a device which

combines both a looped support for a hat and a hook support for a coat or other garment, the hat-loop being supported in a horizontal position above and outside of the 60 hook, so that the brim of the hat will not be bent out of shape or rubbed against the backing to which the support is attached, the twisted wire shank being compact and 65 graceful and sufficiently strong to answer the purposes intended, and the hook being formed of untwisted and parallel loops of wire, which provide the hook with a smooth 70 and non-chafing surface upon which the loop of a coat or other portion of a textile article may be hung without abrading it; and the disposition of the strands of wire forming the hook being such that the weight of an article hung upon the hook will tend to draw the upper strands of the 75 hook down inside of the lower strands, and to thereby draw them in more snugly against the back strands of the hook, and the hook backing counteracting any tendency of the hat support to bend outwardly or 80 downwardly from the back members 6, 7, 8, 9.

The twisting together of the two wires at 7, prevents the opening or spreading of the hook elements, while the angular disposition of the untwisted ends at 8, 8, affords a wide bearing for the device against its backing, thereby preventing its swinging from side to side; while its looped ends 9, 9 afford attachment holes for suitable securing 90 devices, as screws 10, 10.

It is preferable to extend the ends 9, 9 above the plane of the loop 1, or to terminate them below that plane, so that there may be a free line of approach for the screw-driver 95 or other tool which is used to drive the securing elements 10, 10, home.

I have illustrated and described a preferred form of my improved hat rack and coat holder, but I wish it to be distinctly 100 understood that the details of its construction might be modified, as by the use of mechanical equivalents, without departing from the spirit of my invention as claimed.

Having thus described my invention, 105 what I claim and desire to secure by Letters Patent of the United States, is:—

1. A hat rack and coat holder formed of a single piece of wire, having a horizontally disposed, closed loop adapted to surround 110 the crown of a hat, a four ply, untwisted hook, a two ply, offset and twisted loop-

shank extending from said loop to said hook, a two ply, twisted, back section extending away from said hook, and free ends with fastener receiving means.

5. 2. A hat rack and coat holder formed of a single piece of wire, having a horizontally disposed, closed loop adapted to surround the crown of a hat, a four ply, untwisted hook formed of parallel strands, a two ply,

offset and twisted loop-shank extending 10 downwardly and inwardly from said loop to said hook, a two ply, twisted, back section extending away from said hook, the free ends of the wire being bent laterally in opposite directions and then toward each 15 other and terminating in fastening receiving loops.

JOHN W. ETCHELLS.
